CARTON CLOSING MACHINE

Leon Benoit, New York, N. Y.

Application May 22, 1936, Serial No. 81,208

5 Claims. (Cl. 93—2)

The closing machine of the present invention is designed to operate upon an egg carton of the type which embodies two closing flaps which after the carton has been filled with eggs are adapted 5 to be folded inwardly and tucked downwardly along the center of the carton and in closely adjacent relation to the longitudinal division wall of the carton and with their tucking flaps in contact with one another, so that after the closing is complete the top of the carton will present a smooth and plain appearance.

In the closing of a carton of this character, which employs companion cover flaps, it is desirable to fold the cover flaps inwardly toward 15 one another in such a manner that one of the flaps will slightly precede the other in the folding down and tucking in operation, so that the tucking edge of the second or following flap will be guided into its intended position in the longitudinal center of the carton without impedance 20 or interference; and the present invention is designed to accomplish these results by the provision of a properly configured tunnel through which the cartons are progressively advanced and which acts upon the initially upstanding cover 25 flaps in such a way as to turn them inwardly toward one another and cause them to break along the intended folding lines and ultimately press downward into flatwise relation without the intervention of moving parts and merely under the guidance afforded by the walls and roof of the tunnel itself. The only moving parts involved in 30 these operations are those associated with the endless conveyor which advances the cartons into 35 and through the tunnel, and since the speed of advancement is practically unlimited, the carton covers can be folded down and closed with great rapidity and in a certain and accurate manner.

In the present embodiment of the invention I 40 have provided dating rolls at the entering end of the tunnel and a sealing device at the terminus of the tunnel, but these appliances are optional and they may be employed or omitted as desired.

Further objects and details will appear from 45 the description of the invention in conjunction with the accompanying drawings, wherein,—

Figure 1 is a side elevation of the machine embodying the optional dating and sealing appliances;

Fig. 2 and Fig. 3 in conjunction show a plan view of the entire machine;

Fig. 4 is a side elevation of the tunnel;

Fig. 5 is an inner or under face view of the tun- 55 nel;

Fig. 6 is a view showing the throated entering end taken on line 6 of Fig. 4;

Fig. 7 is a view showing the terminus of the tunnel taken on line 7 of Fig. 4;

Figs. 8 to 25 inclusive are cross sections showing the configuration of the tunnel on the various section lines indicated in Fig. 4;

Fig. 26 is a sectional elevation of the dating rolls;

Fig. 27 is a sectional detail taken on line 27 10 of Fig. 26; and

Fig. 28 is a cross sectional view showing the dating rolls in elevation.

The machine as a whole embodies a frame comprising elevated side rails 30 supported upon legs or standards 31 and serving to support a suitable bed plate 32 which projects at each end beyond the standards or legs 31 and is additionally supported above longitudinal extension bars 33 and 34 which are braced and supported by brace bars 35 and 36 connected with the legs or standards 31, giving to the frame structure as a whole the appearance of a table with extensions at each end.

The bed plate is provided within its center portion with a longitudinally extending slot or opening 37 which affords a clearance for the upper turn of an endless conveyor chain 38 at recurrent intervals with lugs or projections 39 which on the upper turn project above the level of the bed plate and are adapted to engage the cross partition walls of the carton, as well indicated in Fig. 26, the lugs being spaced to engage the alternate cross partitions, and the conveyor chain is supplemented by two endless feeding strips 38a, one on either side of the chain, which move in unison therewith and serve to support the cartons during their period of advance, the endless feeding strips being carried by end rollers, one of which is mounted upon the shaft 88.

The cartons are of the form above shown in Figs. 6 and 7 and comprise a body portion which is centrally folded to afford a two-ply longitudinal partition 40 from which the body walls diverge to afford inner base members 41 which are upturned to afford side walls 42 and upstanding cover flaps 43 terminating in tucking flaps 44 separated from the cover along a scored line 45. The body of the carton is divided into cells by the provision of cross partitions 46, which extend through suitable slots in the body walls so that the cross partitions are exposed at the base and along the lower sides of the carton.

The carton advances to the machine with the cover flaps upstanding as in Fig. 6, and emerges 55

from the machine with the cover flaps turned down into plane or flush relation with one another and with the tucking flaps turned inwardly and lying adjacent to the longitudinal partition 40.

The cartons are fed to the endless chain upon an endless conveyor belt 47 which passes around rollers 48 and 49, the top turn of the endless conveyor belt being flush with the surface of the bed plate.

The cartons with their cover flaps upstanding advance between spaced throated guide bars 50, which are supplemented at their inner ends by upwardly sloping outer guide bars 51 of arcuate formation from end to end, which have the effect of throwing the cover flaps inwardly to upstanding relation in the event that they have been turned down outwardly beyond the sides of the carton. The guide bars 50 are also supplemented by an inner guide 52 having the form of an open wedge with its apex presented toward the advancing cartons, so that in the event the cover flaps have been pressed inwardly they will be elevated to vertical position, which is the intended position to be occupied by the cover flaps at the moment of entering the tunnel 53, which performs the closing operations.

The tunnel, as shown, is in the form of a hinged casting whose inner configuration is illustrated in the cross sectional views from 8 to 25 inclusive, and mounted on each side upon lugs 54, 55, 56, so that it stands above the bed plate of the table and has its inner side wall surfaces in substantial register with parallel spaced side guide bars 57 which constitute continuations of the guide bars 50 and extend from end to end of the machine in properly spaced relation to embrace the sides of the cartons and maintain them in processional relation throughout the period of their advance through the machine.

The lugs 54, 55, 56, on each side, are provided with tongues 58 which cooperate with bifurcated lugs 59 on the tunnel wall in affording a connection on each side, and in order to readily swing the tunnel upwardly without bodily removing it, removable pintles 60 are provided on one side (Figs. 2 and 26) which coact with similarly positioned fixed pintles 61 on the other side, so that, after the withdrawal of the removable pintles, the tunnel can be swung back on the hinged connection thus afforded to expose the interior.

The tunnel is throated at its entering end 62, which at this point and for a short distance therefrom has its top wall or roof 63 of substantially conical uninterrupted formation with inwardly converging side walls 64, which tend to bring the upstanding cover flaps into vertical relation and as the cartons advance to cause the tucking flaps 44 to bend or fold along the score lines 45, as indicated in Fig. 6.

Beginning with the section line 8 and running through to the section line 22, in Fig. 4, the roof of the tunnel is divided by a depending wedge shaped center rib 65 whose lower inverted ridge 66 stands at substantially the same horizontal level throughout, although the depth of the center wedge progressively decreases by reason of the sloping configuration of the roof of the tunnel which continues to the section line 20, after which the roof maintains the same low level to the end of the tunnel (see Fig. 4). The width or thickness of the center rib 65 at its upper edge or point of emergence into the roof of the tunnel progressively decreases toward the inner end of the rib, so that at its point of termination at the

section line 22 it presents merely the configuration of a depending blade of substantially the thickness of the ridge edge 66. The provision of the wedge rib thus divides the tunnel throughout about two-thirds of its extent into two parallel channels, each having a progressively varying cross sectional configuration computed with reference to the requirements of the operation involved in progressively bending inwardly the cover flaps 43 and guiding the tucking flaps 44 inwardly and downwardly into the center channel provided for their reception in the body of the cartons adjacent the longitudinal partition 40 thereof.

By observing the sectional views 8-25, it will be noted that throughout the tunnel the base portion 67 of each of the side walls remains substantially uniform for a distance and then narrows slightly to permit the passage of the upper portion of the carton body. The base portion 67 merges into an upper wall section 68 of progressively inwardly converging configuration on its inner or guiding surface, which it will be noted progressively inclines from substantially verticality in Fig. 8 more and more toward the horizontal until the section line 18 is reached, at which point the wall surface 68 is divided by a progressively depending channel 69 which divides the wall surface 68 into outer and inner sections 68^a and 68^b, presenting the same plane and being separated by the channel 69 to reduce the friction imparted to the progressively lowering cover flaps.

The wall sections 68^a, throughout the major extent of the tunnel from section lines 8 to 17, merge into an outer roof wall 70 which lies at a progressively increasing angle to the side wall 68 and combines with the contiguous wall of the center wedge rib 65 in affording the roof of each of the tunnel sections. The wall sections 70 on opposite sides of the tunnel are slightly varied in configuration for the purpose of imparting the necessary bending and guiding movements to the right hand cover flap and tucking flap in somewhat accelerated ratio to the corresponding movements imparted to the left hand cover flap, for the purpose of causing the right hand flap to reach the final folding and tucking position somewhat in advance of its companion, and for this purpose the changes in angularity between the side and top walls on the right hand side are somewhat more accentuated than on the left hand side. Thus it will be noted that the top wall 70 in Fig. 12 has already been lowered to a sufficient degree to make an acute angle with the adjacent side wall 68 on the right hand side of the figure, while the relation of the corresponding parts on the left of the figure affords an obtuse angle. It will also be noted that while the width of the side walls 68 and the top walls 70 remains substantially constant throughout, in order to subtend the area presented by the cover flaps and tucking flaps respectively, and to initiate and progressively increase the bending along the score lines, the angularity of these two walls to one another increases more rapidly on the right side than on the left side, with the result that, in Fig. 15, the wall 70 has throughout combined with the surface of the center rib on the right hand side and eliminated the angle between these two surfaces theretofore maintained.

On section line 17, the left hand wall surface 70 has likewise eliminated said angle with the center wedge, and from that point on the width of the wall 70 progressively decreases to section 75

22, at which point the center wedge terminates, so that thereafter the remnants of the wall 10 unite and at section 25 present an unbroken flat surface. In other words, it will be noted in effect that from section line 14 to the terminus of the center wedge the identity in structure between the top wall 10 and the wedge itself becomes progressively merged into a single structure.

10 By observing Figs. 17 and 19, it will be noted that the right hand tucking flap precedes the left hand tucking flap in entering the space afforded in the center of the carton for the reception of the flaps, with the result that the right hand flap will afford a sliding surface for the left hand flap, thus tending to guide the latter evenly and uniformly into the space provided therefor. By observing section 22, it will be seen that the two flaps have been pressed downwardly to a uniform relation, and at this point the division afforded by the wedge rib is no longer required, and the remainder of the operation merely necessitates the application of uniform pressure from above upon both of the flaps in unison, which occurs throughout the sections 23 to 25.

It will also be noted that the spacing of the lower or base side of the walls 67 remains constant through sections 8 to 12, and is thereafter reduced slightly through sections 13 and 14, with a further reduction through sections 15 to 20, after which the spacing remains constant throughout. This has the effect of permitting the carton throughout the first portion of its journey to move with considerable freedom through the tunnel and without undue confinement of the side walls, which is desirable in the initial stages of bending the cover and tucking flaps along their score lines, but as the middle region of the tunnel is reached the side walls begin to converge slightly, so that during the final tucking operations, and particularly during the down pressing operations performed after the carton has reached the position indicated in Fig. 22, the sides of the carton body will be closely confined against spreading while the necessary force is applied along the center line to effect the final stage of insertion of the tucking flaps. In this position, therefore, the outer remnants of the wall surfaces 68^a will lie in the same plane with the surfaces 70 in the center, which brings the two cover flaps into a plane or flat closed relation across the top of the carton.

In general it may be said that the configuration of the side walls and roof portions of the tunnel is such as to effect a progressive bending of the initially upstanding cover and tucking flaps which causes these portions of the carton to bend along the score lines to progressively increasing angularity with respect both to the said carton walls and the angular relation of the tucking flaps to the cover flaps. At the initial stage of the operation the tucking flaps stand in substantially the same vertical plane with the cover flaps themselves, but during the initial portion of the travel through the tunnel the tucking flaps will be rapidly bent to right angles and thereafter to acute angular relation with the cover flaps, so that the edges of the tucking flaps, during an intermediate portion of the operation, will be brought to a distinctly acute angular relation to the cover flaps, in order to present themselves toward the carton slot in substantially vertical edgewise relation and with one of the tucking flaps leading or in advance of the

other to facilitate the entering operation. This acute angular relation of the parts occurs during the intermediate stage only, since the final operation serves to restore the cover flaps and tucking flaps to right angle relation and with their surfaces throughout in register with one another.

During the medial portion of the carton travel, the presence of the wedge shaped center rib is required to separate the tucking flaps from one another and direct them downwardly on each side in unequal relation, but during the terminal portion of the operation, after the tucking flaps have contacted one another as in Figs. 19 to 22, the separating function of the wedge rib is no longer required, so that it terminates at section 22, thereby allowing a slight further inward movement of the tucking flaps toward one another during the terminal stage of the operation.

The present machine, in the form shown, makes provision for the dating of the carton cover flaps before the same are tucked inwardly and closed, and also makes provision for the sealing of the carton after closure, and although the presence of the dating and sealing appliances is not required in connection with the closing operations within the tunnel, a brief description of these features will now be given.

Adjacent the throated entering end of the tunnel are located a pair of standards 71, 72 which support an elevated bridge bar 73. The bridge bar affords a journal mounting for dating wheel shafts 74, each of which at its lower end carries a dating roll 75 which coacts with a serrated idle roll 76, the parts being so located as to cause the upstanding cover flaps to pass between the bite of the respective pairs of dating rolls. The shafts 74 carry bevel pinions 77 meshing with beveled pinions 78 on a drive shaft 79 carried by journal standards 80 mounted upon the bridge bar 73. A sprocket wheel 81 on the shaft 79 is driven by a sprocket chain 82 carried upon a driving sprocket 83 on a shaft 84 which is driven by a sprocket chain 85 passing over a sprocket 86. The sprocket chain 85 is driven from a suitable sprocket 87 mounted upon a shaft 88, which latter shaft constitutes the driving element for the chain conveyor 38.

Each of the dating rolls 75 is provided on its interior with a slot or recess 89 which receives a dating wheel or wheels 90 adapted to be adjusted to indicate the selected day and month and which when adjusted are held in clamped relation by a thumb screw 91. This arrangement permits each of the cover flaps during its advance toward the tunnel to receive a dating impression or other insignia.

At the delivery end of the tunnel is located a sealing mechanism 92 which serves to feed a strip of gummed tape from a roll 93 and cut off sections thereof through the operations of a knife 94 and to moisten the same and compress the sections thus severed across the top of the carton to seal the cover flaps, but in view of the fact that the sealing mechanism constitutes the subject matter of an independent patent application, Serial No. 84,152, filed June 8, 1936, it is not deemed necessary to describe this mechanism in detail. However, in order to conveniently perform the sealing operation, and to deliver the cartons after being filled and sealed, the endless feeding strips 38^a are extended at the discharge end of the machine sufficiently to carry the cartons through the sealing mechanism and deliver the same at a suitable distance therefrom.

In operation, the filled cartons are delivered upon the conveyor belt 47 with their cover flaps and tucking flaps standing vertically, or nearly so, and thus delivered advance to the right until the cross partitions are engaged by the lugs or teeth upon the chain conveyor, which thus affords a positive feed for carrying the cartons through the tunnel and overcoming the friction occasioned by the progressively convergent relation of the tunnel walls and roof, thus imparting the force necessary to bend in and turn down the cover flaps and tucking flaps in the manner previously described. The guide bars at the mouth of the tunnel serve to insure the proper upstanding position for the cover flaps and to guide the cartons into the mouth of the tunnel, after which the configuration of the tunnel walls imparts the necessary bending and compressive movements to close the carton.

20 The configuration of the tunnel throughout is such as to progressively direct the cover flaps and tucking flaps into the intended lines of movement without sharp or abrupt transitions, which is important in view of the fact that the cartons 25 are of considerable length and the forward ends of the flaps are at all times in a more advanced stage of the closing operation than the trailing or rear ends, so that the closing must be effected by movements which are unequally applied at any 30 particular instant to opposite ends of the flaps. This necessitates the provision of a tunnel of sufficient length to avoid warping or twisting strains which could not easily be accommodated by the flexibility of the material, but with the 35 relative dimensions shown in the accompanying drawings these difficulties are fully overcome, so that a procession of cartons can be fed at a very rapid rate through the machine without any cramping, binding or displacement due to the progressive actions occurring from end to end of 40 the cartons.

At the same time, the side walls of the tunnel are so spaced as to permit the bending operations to occur in the proper direction and degree, and 45 at the terminus of the operation the side walls afford sufficiently close confinement to the carton body to enable downward pressure to be applied in the final stage of the closing operation in order to firmly and closely force the closing flaps into 50 place within the narrow center slot provided for their retention. When thus closed the flaps will be tightly held by the friction thus afforded, so that the final sealing is not in all cases necessary to prevent the opening up of the cover flaps, 55 although desirable to prevent accidental displacement and to insure proper certification of the fact that the carton has not been opened after the filling and dating operations.

Although the invention has been described with 60 full detail, it is not the intention to limit the claims to the exact construction and configuration shown, since modifications thereof may be made without departing from the spirit of the invention.

65 I claim:

1. In a carton closing machine adapted to act upon cartons having side walls and an upstanding cover flap terminating in a marginal tucking flap adapted when closed to enter the body of the 70 carton, an elongated tunnel having side and roof walls and feeding means for carrying the cartons through the tunnel, the tunnel within its entering end having its side and roof walls extending in substantially vertical alignment to permit the 75

cover flap and marginal tucking flap of a carton to stand substantially vertically within the entering end of the tunnel, and said side and roof walls thereafter inclining inwardly and inwardly and downwardly respectively by progressive 5 stages longitudinally of the tunnel in cause progressive bending of the side flap with respect to the associated carton side wall and concurrent and progressive relative bending of the tucking flap with respect to the cover flap, and the tunnel 10 toward its discharging end presenting a substantially horizontal wall surface portion adapted to bring the cover flap into substantially right angle relation to the side wall of the carton body and to force the tucking flap vertically into the 15 interior of the carton body.

2. In a carton closing machine adapted to act upon cartons having side body walls and companion upstanding cover flaps hinged to the respective body walls and terminating in marginal 20 tucking flaps hinged to the respective cover flaps and adapted when closed to have the cover flaps lie in a uniform horizontal plane with the tucking flaps depending vertically into the interior of the carton body, an elongated tunnel having side 25 and roof walls and having between the roof walls through a portion of its length a depending rib dividing the tunnel into two channels, the tunnel within its entering end having the side and roof walls extending substantially vertically to permit 30 entry of the upstanding cover and tucking flap portions of the unclosed cartons, and said side and roof walls of each channel inclining inwardly and inwardly and downwardly respectively by progressive degrees longitudinally of the tunnel to 35 cause progressive folding of the cover flaps with respect to the side body walls of the carton and to cause concurrent and progressive folding of the tucking flaps with respect to the cover flaps, the rib terminating short of the discharging end of 40 the tunnel, and the said walls of the tunnel ultimately presenting acting surfaces in a horizontal plane adapted to compress the cover flaps into uniform horizontal relation to one another and to force the tucking flaps into the interior of the 45 carton body.

3. In a carton closing machine adapted to act upon cartons having body walls and companion cover flaps hinged to and upstanding therefrom and terminating each in a hinged marginal tucking flap, the cover flaps adapted when closed to lie in a uniform horizontal plane with the tucking flaps depending vertically into the interior of the carton body, a tunnel having side and roof walls and feeding means for carrying the cartons through the tunnel, the tunnel within its entering end having its walls spaced sufficiently and being throated to receive the cover flaps and marginal tucking flaps standing substantially vertically, the tunnel being divided throughout a portion of its 60 length into two channels, each having lower and upper side walls and a roof wall, the upper and lower portions of the side walls of the respective channels being configured to extend with 65 relation to one another at angles progressively approaching a right angle, and the upper side walls and roof walls progressively subtending angles of lesser degree and configured to concurrently bend the tucking flaps through varying angular relationships to the cover flaps and into acute 70 angular relationship thereto, and the interior of the tunnel toward its discharging end presenting its acting surfaces in substantially horizontal relation to one another and in position to cause the cover flaps to lie horizontally across the carton 75

body and to force the tucking flaps inwardly into the interior of the carton body.

4. In a carton closing machine adapted to act upon cartons having side walls and companion upstanding cover flaps hinged respectively thereto and terminating each in a marginal tucking flap hinged to the associated cover flap, the carton being adapted when closed to have the cover flaps lie in a uniform horizontal plane with the tucking flaps depending vertically into the interior of the carton body, a tunnel having side and roof walls and feeding means for carrying the cartons through the tunnel, the tunnel within its entering end having its walls spaced sufficiently to receive the cover flaps and marginal flaps standing vertically, and the tunnel being provided throughout a portion of its length with a central longitudinal rib dividing the tunnel into two channels, each channel having a side wall consisting of upper and lower portions, a roof wall and a rib wall, the upper and lower portions of the side walls of the respective channels standing initially in substantially vertical relation to one another, and progressively thereafter subtending decreasing angles ultimately approaching substantially right angle relationship to cause the cover flaps to swing inwardly at progressively more abrupt angles to the side walls of the carton throughout a range of movement of substantially 90° , and the angle subtended between the roof wall and the upper side walls of each channel being progressively decreased and ultimately assuming an acute angular relationship to cause the tucking flaps to concurrently assume a progressively increasing hinging movement with respect to the cover flaps, the tunnel toward its discharging end presenting acting surfaces progressively approaching plane horizontal relationship to one another for ultimately bringing the cover flaps into horizontal closing relation with the tucking flaps entering vertically into the carton body.

5. In a carton closing machine adapted to act upon cartons having side walls and companion

upstanding cover flaps hinged respectively thereto and terminating each in a marginal tucking flap hinged to the associated cover flap, the carton being adapted when closed to have the cover flaps lie in a uniform horizontal plane with the tucking flaps depending vertically into the interior of the carton body, a tunnel having side and roof walls and feeding means for carrying the cartons through the tunnel, the tunnel at its entering end having its walls spaced sufficiently to receive the cover flaps and marginal flaps standing vertically, and the tunnel being provided throughout a portion of its length with a central longitudinal rib dividing the tunnel into two channels, each channel having a side wall consisting of upper and lower portions, a roof wall and a rib wall, the upper and lower portions of the side walls of the respective channels standing initially in substantially vertical plane relation to one another, and progressively thereafter subtending decreasing angles ultimately approaching substantially right angle relationship to cause the cover flaps to swing inwardly at progressively more abrupt angles to the side walls of the carton throughout a range of movement of substantially 90° , and the angle subtended between the roof wall and the upper side walls of each channel being progressively decreased and ultimately assuming an acute angular relationship to cause the tucking flaps to assume a progressively increasing hinging movement with respect to the cover flaps, the tunnel toward its discharging end presenting acting surfaces progressively approaching plane horizontal relationship to one another for ultimately bringing the cover flaps into horizontal closing relation with the tucking flaps entering vertically into the carton body, the angular transition of one of the channels being at an increased ratio as compared to the angular transition of the other channel to cause one of the tucking flaps to advance into the interior of the carton body in advance of the other.

LEON BENOIT.
